CLAIM

We claim the ornamental design for a display screen or portion thereof with animated graphical user interface of a base station for a surgical probe, as shown and described.

DESCRIPTION

FIG. 1 is a front view of a first image in a sequence for a display screen or a portion thereof with an animated graphical user interface, according to a first embodiment;

(Continued)

FIG. 2 is a front view of a second image in a sequence for a display screen or a portion thereof with an animated graphical user interface, according to a first embodiment; FIG. 3 is a front view of a third image in a sequence for a display screen or a portion thereof with an animated graphical user interface, according to a first embodiment; FIG. 4 is a front view of a fourth image in a sequence for a display screen or a portion thereof with an animated graphical user interface, according to a first embodiment; FIG. 5 is a front view of a fifth image in a sequence for a display screen or a portion thereof with an animated graphical user interface, according to a first embodiment; FIG. 6 is a front view of a sixth image in a sequence for a display screen or a portion thereof with an animated graphical user interface, according to a first embodiment; FIG. 7 is a front view of a seventh image in a sequence for a display screen or a portion thereof with an animated graphical user interface, according to a first embodiment; FIG. 8 is a front view of a first image in a sequence for a display screen or a portion thereof with an animated graphical user interface, according to a second embodiment; FIG. 9 is a front view of a second image in a sequence for a display screen or a portion thereof with an animated graphical user interface, according to a second embodiment; FIG. 10 is a front view of a third image in a sequence for a display screen or a portion thereof with an animated graphical user interface, according to a second embodiment; FIG. 11 is a front view of a fourth image in a sequence for a display screen or a portion thereof with an animated graphical user interface, according to a second embodiment; FIG. 12 is a front view of a fifth image in a sequence for a display screen or a portion thereof with an animated graphical user interface, according to a second embodiment; FIG. 13 is a front view of a sixth image in a sequence for a display screen or a portion thereof with an animated graphical user interface, according to a second embodiment; FIG. 14 is a front view of a seventh image in a sequence for a display screen or a portion thereof with an animated graphical user interface, according to a second embodiment;

FIG. 15 is a front view of a first image in a sequence for a display screen or a portion thereof with an animated graphical user interface, according to a third embodiment; FIG. 16 is a front view of a second image in a sequence for a display screen or a portion thereof with an animated graphical user interface, according to a third embodiment; FIG. 17 is a front view of a third image in a sequence for a display screen or a portion thereof with an animated graphical user interface, according to a third embodiment; FIG. 18 is a front view of a fourth image in a sequence for a display screen or a portion thereof with an animated graphical user interface, according to a third embodiment; FIG. 19 is a front view of a fifth image in a sequence for a display screen or a portion thereof with an animated graphical user interface, according to a third embodiment; FIG. 20 is a front view of a sixth image in a sequence for a display screen or a portion thereof with an animated graphical user interface, according to a third embodiment; and, FIG. 21 is a front view of a seventh image in a sequence for a display screen or a portion thereof with an animated graphical user interface, according to a third embodiment. In the drawings, the broken line showing of a device and display screen with graphical user interface is included for the purpose of showing portions of the article which form no part of the claim. The appearance of the display screen or portion thereof with animated graphical user interface sequentially transitions between the images shown within FIGS. 1-7 for the first embodiment. The appearance of the display screen or portion thereof with animated graphical user interface sequentially transitions between the images shown within FIGS. 8-14 for the second embodiment. The appearance of the display screen or portion thereof with animated graphical user interface sequentially transitions between the images shown within FIGS. 15-21 for the third embodiment. The process or period in which one image transitions to another forms no part of the claimed design.
